UNITED STATES PATENT OFFICE.

WILLIAM NEWTON BEST, SR., OF NEW YORK, N. Y.

GAS-BURNER.

1,042,872.

Specification of Letters Patent.

Patented Oct. 29, 1912.

Application filed June 9, 1909. Serial No. 501,010.

To all whom it may concern:

Be it known that I, WILLIAM NEWTON BEST, Sr., a citizen of the United States, and a resident of the city of New York, borough 5 of Brooklyn, in the county of Kings and State of New York, have invented a new and Improved Gas-Burner, of which the following is a full, clear, and exact description.

10 This invention relates to certain improvements in gas burners adapted for heating, the special object of the invention being to so construct the burner that the combustible gas after escaping will become mixed with 15 air and burn closely adjacent the surface of the refractory material, which latter will retain the heat and facilitate the combustion.

20 In my improved burner I deliver the gaseous fuel through a plurality of small openings and substantially parallel to the surface of a refractory block, so that the block will be heated by the burning gas, and, at the same time, will serve to heat the gas 25 and air adjacent the burner. By this construction I secure a greater degree of heat.

25 The invention may be embodied in any form of heating apparatus, and the gas delivery tube and the refractory material be 30 of any suitable form or size, to secure the desired object.

35 Reference is to be had to the accompanying drawings, forming a part of this specification, in which similar characters of reference indicate corresponding parts in all the figures, and in which—

40 Figure 1 is a longitudinal section through a water heater having a burner constructed in accordance with my invention; Fig. 2 is 45 a transverse section on the line 4—4 of Fig. 1; Fig. 3 is a longitudinal section through a portable stove embodying my invention.

45 My improved burner is adapted for heating purposes, and when used for heating, I may employ a second block of refractory material, so that the flame will lie between two substantially parallel blocks.

50 In Figs. 1 and 2, I have illustrated one embodiment of my invention in which the burner is used for heating a water coil in the type of construction commonly known as "instantaneous heaters." In this construction, I utilize an annular burner tube 55 23, supported by a delivery pipe 24 extending diametrically across the burner. This

delivery tube is supported intermediate its ends upon a supply conduit 25, or in any other suitable manner. The upper end of the supply conduit 25 may extend above the burner tube, and encircling this extension 60 is an annular block 26 of refractory material. This block may be spaced from the conduit and may be provided with radially-disposed apertures, if desired. The lower end of the block may rest directly upon the 65 cross pipe 24 and the upper end may be held in place and prevented from moving upwardly or laterally by a securing plate 27 connected to the extension of the pipe 25. The burner is supported inside of a sheet 70 metal casing 28 and concentric therewith, and the adjacent portion of the sheet metal casing may have a lining 29 of refractory material. This lining is concentric with the block 26 and is spaced a short distance therefrom to leave an annular passage, at the lower end of which is the annular burner tube 23. The flame rising from the burner is midway between the two refractory surfaces and closely adjacent to each, so that 75 both operate to radiate heat to the mixture as it is formed directly above the openings in the burner tube, and to facilitate combustion and create a higher temperature, the lining block 29 may also be provided with 80 apertures therethrough, if desired. Within 85 the casing is mounted a helical coil 30, down through which water may be delivered, and the upper end of the casing may have a dome-shaped heat deflector 31, perforated 90 to permit the escape of the gases of combustion.

95 Substantially the same construction may be employed in a portable stove. In Fig. 3, I have illustrated a portable stove having a burner identical in form with that shown in Figs. 1 and 2, save that the casing 28^a is not as tall and no water coil is employed. The stove may be supported above the floor by 100 suitable legs 32, and perforations may be provided in the upper portion of the casing instead of in the heat-deflecting top or dome 31^a.

105 It will be noted that the gas escapes vertically through a row of small openings, and substantially parallel to the surface of a block of refractory material closely adjacent thereto. The flame does not play on the block but the block is heated and the heat delivered back to the mixture as it forms near the outlet.

Having thus described my invention, I claim as new and desire to secure by Letters Patent:

1. A gas burner comprising a vertically disposed gas delivery tube, branches extending therefrom in opposite directions, an annular burner tube concentric with said gas delivery tube, and in communication with said branches, an annular block of refractory material, encircling said gas delivery tube and provided with openings, the annular block being disposed within the vertical projection of the annular burner tube, another annular block of refractory material and encircling said first-mentioned block and the annular burner tube, the second-mentioned annular block being spaced from the first-mentioned block and being provided with openings, said second-mentioned block having greater height than said first-mentioned block and extending above and below the same, and a metal casing encircling both of said annular blocks.
2. A gas burner comprising a vertical gas delivery tube, branches extending therefrom, an annular burner tube concentric to said gas delivery tube and connected with said branches, an annular member of refractory material encircling said gas delivery tube and substantially coaxial with and within the vertical projection of said annular burner tube, said block of refractory material being in close proximity to the said burner tube, another block of refractory material encircling said first mentioned block

and said burner tube, and spaced from the first-mentioned block, said second-mentioned block of refractory material being provided with openings, and a metallic casing encircling said second-mentioned block and provided with openings in registry with the openings in said second-mentioned block.

3. A gas burner comprising a vertically disposed gas delivery tube, branches extending therefrom, an annular burner tube connected with and supported by the branches, an annular block of refractory material encircling said gas delivery tube and provided with openings, the annular block of refractory material being supported by the branches, and being disposed within the vertical projection of the annular burner tube, a securing plate connecting the annular block of refractory material with the gas delivery pipe, and another annular block of refractory material encircling said first-mentioned block and the annular burner tube, the second annular block being spaced from the first-mentioned block, and being provided with openings, the said second-mentioned block having a greater height than the first-mentioned block and extending above and below the same.

In testimony whereof I have signed my name to this specification in the presence of two subscribing witnesses.
